CLAIM

The ornamental design for a grinder and extraction device as shown and described.

DESCRIPTION

FIG. 1 is a top perspective view of a grinder and extraction device showing my new design.

FIG. 2 is a bottom perspective view of the grinder and extraction device shown in FIG. 1.

FIG. 3 is a front view of the grinder and extraction device shown in FIG. 1.

FIG. 4 is a top view of the grinder and extraction device shown in FIG. 1; and,

FIG. 5 is a bottom view of the grinder and extraction device shown in FIG. 1.

The rear view, left side view, and right side view are omitted because they are identical to the front view.

The thin solid lines shown in the figures represent contours only and do not illustrate an ornamentation or decoration on the surface of the grinder and extraction device.
